UNITED STATES PATENT OFFICE.

GRANVILLE A. HUMASON, OF HOUSTON, TEXAS.

SWAB.

Application filed June 21, 1926. Serial No. 117,467.

This invention relates to new and useful improvements in a swab.

One object of the invention is to provide a device of the character described specially 5 designed for use in swabbing out and cleaning a well bore and relieving the same of all surplus water and slush preparatory to the production of oil therefrom.

Another object of the invention is to provide 10 a swab of the character described having a plunger which will release the pipe in which the swab works, on down stroke, to minimize the friction with said pipe, but which, upon upstroke, will expand and fit 15 closely within said pipe to prevent the leakage of fluid downwardly between said plunger and pipe.

A further feature of the invention is to provide 20 a swab, of the character described of such construction that in case of an overload the excess load will be released to prevent breakage of the operating stem or other parts.

With the above and other objects in view 25 this invention has particular relation to certain novel features of construction, operation and arrangement of parts, an example of which is given in this specification and illustrated in the accompanying drawings, 30 wherein:—

Figures 1 to 3 inclusive show vertical sectional views of top, intermediate and bottom sections of a complete swab, taken in the order shown.

Figures 4 and 5 show vertical sectional views of an alternative form of construction 35 which may be substituted for certain parts shown in Figures 1 to 3.

Figure 6 shows a plan view of one of the 40 plunger sections.

Figure 7 shows a cross sectional view of the swab, taken on the line 7—7 of Figure 2.

Figure 8 shows a cross sectional view taken on the line 8—8 of Figure 5, and

Figure 9 shows a vertical sectional view of 45 a cage that may be employed.

It may be here noted that the form of device shown in Figures 1, 2 and 3, assembled, in due order illustrate a complete swab, in 50 themselves, or, if desired, the bottom sections shown in Figures 4 and 5 may be attached in the order named, onto the bottom of the form shown in Figures 1, 2, and 3 and the operating stem connected to the upper end 55 of the tubular mandrel shown, through the

cage illustrated in Figure 9, and the over-weight spring and connecting parts shown in Figures 1 and 2, removed all as herein-after explained, and a practical type of swab thus produced.

Referring now more particularly to the drawings, wherein like numerals of reference designate similar parts in each of the figures the numeral 1 designates the pipe in a well bore to be swabbed.

The numeral 2 designates the plunger, as a whole. This plunger is mounted on an operating mandrel 3, tubular in form. The mandrel has a plurality of sections, square in cross section arranged, one above the other and downwardly flared, thus forming the external flat bearing faces 4 and the downwardly facing abutments, or shoulders 5. The faces 4 also are formed with vertical tenons 6, as shown. The plunger is formed of a surrounding sleeve 7, of rubber or other suitable material, and within it the metallic sections 8 whose inner sides are formed to conform to the contour of and fit against the respective faces 4 and these sections have vertical mortises 9 to receive the respective tenons 6 and are also provided with the inside shoulders 10 adapted to work opposite the shoulders 5. The lower ends of the plunger sections 8 have the external 80 upwardly facing grooves 11 to receive and retain the reduced lower end of the sleeve 7 and beneath the lower end of the plunger there is a retaining ring 12 which is locked in place by the lock sleeve 13, which is screwed onto the lower end of the mandrel. The upper end of the plunger is formed with a cap plate 14 which is connected to the respective sections 8 by set bolts 15 and this plate has a marginal depending annular 85 flange 16 which surrounds the upper end of the sleeve 7. Abutting this cap plate 14 is the upper end plate 17, provided with a stuffing box 18 and the upper end of the mandrel works through a central bearing in the cap plate 14 and through said stuffing box 18, as well.

An operating stem 19 has its lower end screwed into the reduced upper end of an elongated, bell shaped housing 20, whose lower end is formed with an internal annular flange, or seat 21. A coil spring 22 is supported within the housing 20 upon said seat and a tubular nipple 23 is fitted through said spring and its upper end has an en-

larged head 24 which rests on said spring while its lower end is connected to the upper end of the mandrel through the coupling 25. The housing 20 has a plurality of outlet side slots 26 and the upper end of the nipple 23 has a flared valve seat 27 which is controlled by the valve 28. This valve is fixed to the lower end of the valve stem 29 which works through the guide 30 in the housing 20, and 10 whose upper end is formed with an enlarged head 31.

The swab, as above specifically described, may be let down into the pipe 1. As it is lowered the mandrel will move downwardly 15 relative to the sections 8, thus contracting them, until the shoulders 5 abut against the opposing shoulders 10 and the plunger will thus be contracted to lessen the friction of the sleeve 7 against the pipe 1 and as the 20 swab descends the fluid will pass up through the tubular mandrel 3 and nipple 23 and lift the valve 28 and pass out through the outlets 26. The swab may then be pulled upwardly through the stem 19, and with a 25 normal load the valve 28 will seat and prevent the back flow of fluid. In case of an overload, the spring 22, of sufficient strength to carry only a normal load, will compress, permitting the guide 30 to engage the head 30 29 and to lift said valve and thus permitting the excess load to escape back through said nipple and mandrel.

Referring to Figures 4 and 5 the numeral 31 designates a barrel into the upper end of 35 which a coupling 32 may be screwed and the lower end of the mandrel 3 connected into the upper end of said coupling 32. A block 33 is screwed into the lower end of this barrel and upstanding from this block is a 40 tube 34 whose upper end is controlled by the upwardly opening valve, 35, which is confined within the cage 36, attached to the upper end of said tube. This valve carries a stem 37 which works through a suitable 45 bearing in the upper end of said cage.

The lower end of the tube channel separates into radial passages 38, through the block 33 and said block also has vertical passageways 39 therethrough, arranged in 50 staggered relation with respect to the passageways 38.

Threaded onto the lower end of the block 33 there is a valve cage 40, having an internal chamber 41 which the passageways 39 enter, and this chamber has a reduced downward discharge opening 42 controlled by the valve 43. This valve has a depending stem 44 which works through a central bearing 45 in the lower end of the cage 40, and a coil 60 spring 46 surrounds said stem 44 and is interposed between the valve 43 and the bearing 45.

In operating this form of the swab the coupling 25 is detached from the mandrel 3 65 and the housing 20 and its appendants are

removed and the cage 47 is connected to the upper end of the mandrel 3 and the stem 19 then connected to said cage 47.

The swab is then let down into the pipe 1 and the fluid will pass in through the 70 passageways 38 and will lift the valve 35 and pass on up above the swab, and upon upstroke with normal load, the valve 35 will close to prevent the back flow of the fluid, but in case of an overload the valve 43 will 75 be forced open until the excess fluid flows back through the discharge opening 42 and thereupon the spring 46, which is capable of carrying the normal load, will close the valve 43.

In each form of swab the upward movement of the mandrel 3 is limited relative to the plunger by the ring 12 and the downward movement is limited by the shoulders 5 and 10 and the expansion and contraction 85 of the plunger is thereby controlled, and the range of such expansion and contraction may be varied by adjusting the sleeve 13 up or down on the mandrel.

What I claim is:—

1. In a swab a mandrel having a plurality of downwardly flared sections, one above the other and whose lower ends terminate in shoulders, a surrounding expandable sleeve, a plurality of expandable sections around the mandrel having inside faces which work against the mandrel sections and formed with shoulders which oppose the shoulders of the mandrel, the lower ends of said expandable sections having upwardly facing grooves into which the lower end of the sleeve fits.

2. In a swab a mandrel having a plurality of downwardly flared sections, one above the other and whose lower ends terminate in shoulders, a surrounding expandable sleeve, a plurality of expandable sections around the mandrel having inside faces which work against the mandrel sections and formed with shoulders which oppose the shoulders of the mandrel, the lower end of the plunger sections and the abutting lower end of said sleeve being provided, one with an annular groove into which the other fits.

3. In a swab a mandrel having a plurality of downwardly flared sections, one above the other and whose lower ends terminate in shoulders, a surrounding expandable sleeve, a plurality of expandable sections around the mandrel having inside faces which work against the mandrel sections and formed with shoulders which oppose the shoulders of the mandrel, the lower end of the plunger sections and the abutting lower end of said sleeve being provided, one with an annular groove into which the other fits, an abutment secured to the mandrel beneath said expandable sections, a cap plate connected to the upper ends of said ex- 130

pansible sections and formed with a marginal depending annular flange which engages the upper end of said sleeve.

4. In a swab a mandrel having a plurality of downwardly flared sections, one above the other and whose lower ends terminate in shoulders, a surrounding expansible sleeve, a plurality of expansible sections within the sleeve having inside faces which work against the mandrel sections and formed with shoulders which oppose the shoulders of the mandrel, the lower end of the plunger sections and the abutting lower end of said sleeve being provided, one

with an annular groove into which the other fits, an abutment secured to the mandrel beneath said expansible sections, a cap plate connected to the upper ends of said expansible sections and formed with a marginal depending annular flange which engages the upper end of said sleeve and an upper end plate abutting said cap plate, the upper end of the mandrel extending through said upper end plate and cap plate.

In testimony whereof I have signed my name to this specification.

GRANVILLE A. HUMASON.
